UNITED STATES PATENT OFFICE.

THOMAS S. HOMANS, OF HEMPSTEAD, NEW YORK, ASSIGNOR TO INTERNATIONAL TYPESETTING MACHINE COMPANY, OF NEW YORK, N. Y., A CORPORATION OF NEW YORK.

ASSEMBLER FOR LINE-COMPOSING MACHINES.

1,149,767.

Specification of Letters Patent.

Patented Aug. 10, 1915.

Application filed June 16, 1913. Serial No. 774,035.

To all whom it may concern:

Be it known that I, THOMAS S. HOMANS, a citizen of the United States, residing at Hempstead, in the county of Nassau and 5 State of New York, have invented new and useful Improvements in Assemblers for Line-Composing Machines, of which the following is a specification.

This invention relates to improvements in 10 line composing machines and more especially to those of the linotype class employing a rotary star wheel which coöperates with the assembling matrices and serves to push them in a direction downwardly and forwardly to stack them in a line in the assembling channel. Frequently, however, it 15 happens that when the matrices fall too closely together or in using very thick matrices, there is insufficient space between the 20 points of the star wheel to allow the matrices to reach the bottom of the assembling channel before they are pushed forward by the following point of the star wheel, thereby causing jamming which interrupts the operation of the machine.

The primary object of the present invention is to provide a star wheel or equivalent assembling stacking device which is not only rotatable but which also has a reciprocatory 30 or shifting axis whereby greater clearance is provided for the falling matrices and heavier or thicker matrices can be used.

To this end, the invention consists in certain improvements, and combinations and 35 arrangements of parts, all as will be herein-after more fully described, the novel features being pointed out particularly in the claims at the end of the specification.

In the accompanying drawing:—Figure 40 1 is a plan view of a portion of the matrix assembling mechanism of machines of this class and embodying the present invention; Fig. 2 is a front elevation of the structure shown in Fig. 1; Fig. 3 is a front elevation, 45 partly in section, of a portion of the assembler including the star wheel, and showing the elements in a different position as compared with Fig. 2.

Similar parts are designated by the same 50 reference characters in the several views.

In the accompanying drawing, the invention is shown in connection with the matrix assembling mechanism as commonly used on line composing machines of the linotype class. It will be understood, however, that

the invention is not restricted necessarily to this particular type of machine and that the invention is not limited to the particular form thereof as shown, as equivalent constructions may be used which will be included within the terms of the claims.

In the present instance 1 designates the assembler plate or bracket which is secured in fixed position to the frame of the machine, and 2 designates the matrix-receiving end of the elevator which provides a channel in which the matrices M are assembled to form a line from which a type slug is subsequently cast. A shaft 3 is mounted in the assembler plate 1, this shaft having a belt pulley 4 fixed to its forward end and tight and loose pulleys 5 fixed to its rear end. Rotary motion is imparted to the shaft 3, and consequently the pulley 4 in the direction indicated by the arrow, by a belt or equivalent means coöperative with one of the pulleys 5. A matrix delivery belt 6 passes over the pulley 4, the upper stretch of this belt moving in a downwardly inclined direction beneath the delivery end of the magazine and serves to convey the matrices delivered from the magazine to the assembler. According to the present invention, the star wheel 7 or equivalent device for assembling and stacking the matrices in the line is reciprocatory or shiftable in a direction longitudinally of the matrix assembling channel. This star wheel in the construction shown is fixed to turn with its driving shaft 8, this driving shaft being journaled in a sleeve or bearing 9, and this sleeve or bearing, together with the shaft 8, is shiftable in a direction toward and from the assembling line of matrices in the assembling channel. In the present instance, the assembler plate 1 is formed with a notch 10 which provides a horizontal guide for the sleeve or bearing 9, the latter being flattened or otherwise shaped to fit in the notch and coöperate with the upper and lower walls thereof. According to the present invention, this star wheel is shifted toward and from the assembling line of matrices while revolving. Different means may be provided for reciprocating and revolving the star wheel in the manner described. The construction shown in the present instance for accomplishing this result embodies a pair of links 11 and 12 which are pivotally connected at their adjacent ends, the opposite end of the link 11 having a bearing 13 100

which is fitted to rotate on a hub 14 which surrounds the bearing for the shaft 3, and the opposite end of the link 12 is formed with a bearing 15 which is rotatably mounted on the sleeve 9 which latter surrounds the shaft 8 of the star wheel. A driving gear 16 is fixed on the shaft 3, another driving gear 17 is mounted on the shaft 8 and is connected thereto by the friction spring 18, and an idler gear 19 meshes with the gears 16 and 17 and is mounted on the same axis which connects the adjacent ends of the links 11 and 12. A crank pin 20 is fixed to the gear 19 at a point which is eccentric to the axis of rotation of this gear, and a link 21 has one end attached to this crank pin, the opposite end of said link 21 being connected to a stationary pivot 22.

Rotary motion applied to the shaft 3 through one of the driving pulleys 5 causes the pulley 4 which drives the matrix delivery belt 6 to move in the direction indicated by the arrow. This motion of the shaft 3 will be transmitted through the idler gear 19 to the gear 17, the latter causing the star wheel 7 to revolve in the direction of the arrow in Fig. 2. As the gear 19 revolves, the link 21 will hold the crank pin 20 thereon at a constant distance from the stationary pivot 22, and consequently the links 11 and 12 will be shifted toward and from alinement, as will appear from Figs. 2 and 3, thereby causing the star wheel to reciprocate or shift in a direction longitudinally of the matrix assembling channel. Continuity in the driving of the rotary star wheel is obtained as the idler gear 19 shifts with the links 11 and 12, and its axis is thereby maintained at a constant distance from the axes of the gears 16 and 17. Each complete revolution of the idler gear reciprocates the star wheel toward and from the assembling line of matrices. As the star wheel recedes from the assembling point, it provides more space in which the matrices may drop to the bottom of the channel in the elevator, thereby insuring correct assembling of the matrices whether they drop closely together or whether very thick or heavy matrices are used, this additional space for the accommodation of the dropping matrices being obtained without increasing the size of the star wheel.

I claim as my invention:

1. In a line composing machine, a matrix assembling channel, a rotary star wheel for assembling matrices into line in said channel, and means for positively reciprocating

the star wheel bodily in a rectilinear direction transverse to its axis of rotation.

60

2. In a machine of the linotype class, a horizontal assembling channel, a revoluble assembler mounted on an axis arranged transversely of said channel, and means for positively reciprocating the assembler in a direction transverse to its axis of revolution.

65

3. In a line composing machine, the combination with a matrix assembling channel, of an assembler arranged at the entrance to said channel and having means for rotating it and means for reciprocating the assembler in a rectilinear direction longitudinally of said channel and transverse to the axis of rotation of the assembler.

70

4. In a machine of the linotype class, a matrix assembler mechanism embodying a horizontal assembling channel, a star wheel revoluble on a horizontal axis arranged transversely of said channel, and means for positively reciprocating the star wheel in a direction transverse to its axis.

75

5. In a line composing machine, the combination with a matrix assembling channel, an assembler located at the entrance to said channel and reciprocable in a rectilinear direction toward and from the same and in parallelism therewith, and means for simultaneously and positively revolving and reciprocating the assembler.

80

6. In a machine of the linotype class, the combination with a matrix assembling channel, of a star wheel revolvably mounted at the entrance end thereof and having means for guiding it to move toward and from the channel in a direction parallel with the length thereof, a driving shaft having a driving gear thereon, a driving gear operatively connected to the star wheel, a pair of links pivotally connected at their adjacent ends and also pivotally connected at their remote ends to said driving shaft and star wheel, an idler gear mounted concentrically with the pivot connecting the adjacent ends of said links and co-operative with the gears on the driving shaft and star wheel, and a link eccentrically connected to the idler gear for flexing said links during the operation of the star wheel.

85

In testimony whereof I have hereunto set my hand in presence of two subscribing witnesses.
